UNITED STATES PATENT OFFICE.

JOHN PERRETT, OF NEW YORK, N. Y.

TOY WALKER.

Application filed February 1, 1924. Serial No. 689,958.

To all whom it may concern:

Be it known that I, JOHN PERRETT, a citizen of the United States, and a resident of the city of New York, borough of Manhattan, in the county and State of New York, have invented a new and Improved Toy Walker, of which the following is a full, clear, and exact description.

This invention relates to a toy walker for children. An object of the invention is to provide a simple, economical and efficient device whereby a child can seat himself on the device and by manipulating it travel rapidly and easily from point to point.

Another object concerns the provision of means whereby the movement from place to place is effected in a very simple manner, affording considerable amusement to the child and requiring him to develop a degree of skill in the operation of the toy and in balancing himself thereon which is of considerable benefit to him.

The invention is illustrated in the drawings, of which—

Figure 1 is a perspective view of the device with a child seated thereon;

Fig. 2 is a side elevation; and

Fig. 3 is a plan view of the device.

The form of the invention shown in the drawings is a preferred form, although it is understood that modifications in the construction and arrangement of the parts and in the character of the materials used may be adopted without departing from the spirit of the invention as set forth in the appended claims.

The general conception of the device comprises a frame, which includes a curved runner which extends over considerable of the arc of a circle, connected to a seat plate or seat-supporting portion by suitable rigid connecting members. On this frame is mounted a pivoted seat, and to it is also fastened a handle which the child grasps in both hands. In seating himself upon the frame, the child grasps the handle and holds himself upright on the seat with his feet on the ground beneath him. His first operation is to slightly relieve the device of his weight while he pulls the handle closely toward him, thus drawing the rear portion of the runner as nearly directly under him as possible. Then he allows his weight to fall on the seat and, removing his feet ever so slightly from the ground, to bend forward against the handle, whereby the de-

vice is rocked forward on the runner, meanwhile the seat maintains its horizontal relation because it is pivoted and can move with respect to the frame. In rocking forward, 60 the forward end of the runner comes beneath the child's feet, and this rocking motion causes a progression along the floor. When the forward end of the runner is disposed beneath the child, his feet are placed 65 on the ground, his weight is slightly lifted from the seat and the handle is pulled toward him again, whereupon he resumes his seat on the frame and repeats the operation. This operation is quickly appreciated by 70 the child, whereby he can travel rather rapidly from point to point. The fact that there is only one runner requires him to maintain a certain degree of balance, which is of considerable benefit to him. The 75 rapidity with which a child can travel by using this device has been found to be quite astonishing. Of course, the larger the child operating the device, the longer the runner can be made and, consequently, the more 80 ground can be traveled in a given space of time.

As shown in the drawings, which represent the preferred form, the device comprises a runner 1 curved preferably in the 85 arc of a circle approximately 120°. This runner is connected by means of rigid members 2 and 2^a, 3 and 3^a, and 4 and 4^a at different points throughout its length, with a seat-supporting plate 5 to which a seat 6 is 90 pivoted. A handle portion 7 is connected to the rigid members 2 and 2^a and 3 and 3^a at points 7^a and 7^b to extend beyond the members 2 and 2^a, and is provided with a hand-engaging portion or bar 8. 95

As shown in Fig. 1, the child 9 is seated on the seat 6 and can move the device beneath him by raising his weight off the seat by either pulling the handle toward him or pushing it away from him. The seat being 100 pivoted permits it to be kept as far as possible in the horizontal position regardless of the relation of the frame with respect to the child.

Assuming that the child is seated on the 105 seat 6 and has drawn the handle 7 as closely as possible to his body while supporting his weight on his feet slightly off the seat 6, then the connecting members 4 and 4^a will 110 assume a substantially vertical position beneath him. As soon as this position is effected, he allows his weight to rest on the seat

6 and throws himself forward against the handle 7 which causes the frame to rock or roll forward until the connecting members 2 and 2^a are disposed substantially vertically beneath the seat, which has throughout this rocking motion been maintained in a substantially horizontal position. When this disposition of the parts is achieved, the child places his feet on the ground and lifts his weight off the seat 6 and at the same time 10 pulls the handle 7 forward toward himself, thus bringing the connecting members 4 and 4^a again beneath him, whereupon the operation is repeated. The rapidity of the performance of this cycle of operations governs 15 the speed at which the child can travel from point to point.

This device has been found to be a source of amusement for children and requires of 20 them a sufficient degree of skill in its operation and in balancing themselves upon it to be of considerable benefit to them.

Of course, it is understood that the same principle of operation could be applied to a 25 frame in which there was more than one runner excepting that in this construction it is not thought necessary to show the degree of balance required, which is negligible.

What I claim is:—

30 1. A toy walking device which comprises a frame having a curved runner portion adapted to rest on and to be rolled over the ground, a pivoted seat mounted on said frame, and a handle portion rigidly attached thereto, said seat adapted to be main-

tained in a substantially horizontal position by a person seated thereon independent of the movement of the frame with respect to the ground and the body of the person as it may be moved by said person in traveling 40 over the ground.

2. A toy walking device which includes a frame comprising a curved runner adapted to bear on and to be rolled over the ground, a plurality of rigid members extending from 45 points throughout the length of said runner to a common point, a seat-supporting plate to which said connecting members are attached, a pivoted seat on said plate, and a handle portion connected to said frame and having an end extending therefrom adjacent the seat to be grasped by the hand of the operator.

3. A toy walking device which includes a frame comprising a curved runner adapted to bear on and to be rolled over the ground, a plurality of rigid members extending from 50 points throughout the length of said runner to a common point, a seat-supporting plate to which said connecting members are attached, a pivoted seat on said plate, and a handle portion connected to said frame and having an end extending therefrom adjacent the seat to be grasped by the hand of the operator, said seat adapted to be maintained 55 in a horizontal position by a person seated thereon independent of the movement of the frame by the person seated.

JOHN PERRETT.
